INVENTOR;

William J. Ross

UNITED STATES PATENT OFFICE.

WILLIAM J. ROSS, OF WEST BOYLSTON, MASSACHUSETTS.

IMPROVEMENT IN WINDOW-CASINGS.

Specification forming part of Letters Patent No. 157,224, dated November 24, 1874; application filed March 30, 1874.

To all whom it may concern:

Be it known that I, WILLIAM J. ROSS, of West Boylston, in the county of Worcester and Commonwealth of Massachusetts, have invented certain new and useful Improvements in Window Frames or Casings; and I do hereby declare the following to be a full, clear, and exact description of the same, reference being had to the accompanying drawings which form a part of this specification, and in which—

Figure 1 represents a vertical section on line B C, Fig. 2, of so much of a window-frame and one of the sashes as is necessary to illustrate my present invention. Fig. 2 represents a cross-section through the window-casing and sash on line A B, Fig. 1; and Figs. 3 and 4 represent opposite views of portions of the window-casing on one side, as will be hereafter more fully described.

To enable those skilled in the art to which my invention belongs to make and use the same, I will proceed to describe it more in detail.

My invention is designed to obviate the difficulties and objections incident to the present modes of making the window frames and casings for the purpose of permitting the window-sash to be removed when desired, and also for the insertion of the weights and cords, and for the adjustment of the same when necessary; and consists in the use, for the purposes aforesaid, in window frames or casings, of a removable section, having its upper extension chamfered off on the inner side, so that it can be inserted when the sash is not entirely raised, in conjunction with an overhanging inclined cut in the casing fitting a corresponding inclined cut on the removable section, the parting bead forming a portion of said removable section, all as herein described.

In the drawings, the parts marked A and B represent the lower and upper sash of a window, and the parts marked C D the sides of the window-frame, which, in this case, constitute the side casings and the parting beads—that is, the parts C D are cut or molded upon their inner sides, with proper grooves for the window-sash to work in, with tongues or part-

ing beads *a* between them, thus dispensing with separate pieces or tongues *a*, and also separate pieces for the inside casings to hold the inner sash in place, as shown at *b b*.

By this mode of construction the parts referred to can be made and finished in a much more finished and perfect manner, while saving the expense of screws and other fastenings usually employed for securing the parts in place, especially the parts marked *b b*.

Upon each side of the lower sash separate sections E E are made to fit into corresponding recesses cut out of the window frame and casing, as indicated in the drawings. The upper ends of said parts are made beveling to fit under corresponding shoulders, or overhanging inclined cuts *f* on the fixed parts of the casing, whereby, when the lower ends of the parts E E are secured, said removable sections will be held tightly in place. The lower ends of the parts E E may be held in place by a screw, as shown at *e*, or by pins, as shown at *e*. The upper end or extension of the sections E are chamfered off on the inside, as shown at *g*, so that they may be inserted in place when the sash is not entirely raised.

To remove the sash it is only necessary to run up the lower sash, and then remove one of the pieces E, after which the sash is lowered and one end allowed to enter the space from which the part E was taken, when the other end of the sash will slip by the projection *b* on the opposite side. The upper sash is removed in a similar manner, after the lower sash has been removed, by simply drawing it down.

It will be understood that a section of the parting bead *a* is made with, and forms a part of, the detachable piece E.

Weight pocket-holes F are made in the sides of the pieces or window-jambs C D, whereby, when the sections E E are removed, convenient access can be had to the weights.

Fig. 3 shows an inside view of one of the removable pieces E and a section of the casing to which it is attached; and Fig. 4 represents an outside view of a section of the casing or frame, showing one of the pocket-holes F.

By making the sides of the frame or casing

all in one piece I can make grooves *d* upon the outside of the sash, in which to arrange window-screens, so that they will not have to be removed when the windows are raised, lowered, or removed.

Those skilled in the art to which my invention belongs cannot fail to appreciate the great practical value and importance of my invention, both as regards the expense in fitting the sash-holding devices in place, and the convenience in removing the sash from the window-frame, which can always be done without marring any of the parts, and my invention is applicable as well to the cheapest as the most expensive buildings.

Having thus described my improvements in

window frames or casings, what I claim therein as new, and of my invention, and desire to secure by Letters Patent, is—

The removable section *E*, having its upper extension chamfered off on the inner side, so that it can be inserted when the sash is not entirely raised, in conjunction with an overhanging inclined cut, *f*, fitting a corresponding inclined cut on the removable section, the parting bead forming a portion of said removable section, as and for the purposes shown and described.

WILLIAM J. ROSS.
